HOISTING MECHANISM FOR CHARGING HOPPERS

Filed Jan. 21, 1928

FIG. 2 Andrew S. Johnson
By his Attorney

S. J. Cox

UNITED STATES PATENT OFFICE.

ANDREW S. JOHNSON, OF PLAINFIELD, NEW JERSEY, ASSIGNOR TO RANSOME CONCRETE MACHINERY COMPANY, OF PLAINFIELD, NEW JERSEY, A CORPORATION OF NEW JERSEY.

HOISTING MECHANISM FOR CHARGING HOPPERS.

Application filed January 21, 1928. Serial No. 248,308.

The improvements herein relate primarily to hoppers or buckets adapted to be elevated, but more particularly to that type of hopper or vessel which is pivoted so as to accomplish arcuate travel, and to the means for elevating same. Buckets or loaders of this type are commonly employed in concrete mixers, are frequently called loading skips or hoppers, and are constructed and arranged to rest on the ground below the charging opening of the mixer so as to receive the aggregates to be mixed from barrows, shovels or in any other manner, near the ground level. The bucket is usually so mounted that as it is raised it also tips or tilts and discharges its load into the mixer. A cable leading from a drum on the mixer frame to the bucket is commonly employed for elevating same. The present improvements are chiefly designed to afford a better connection between the cable and bucket, which equalizes the pull of the former, as well as to facilitate repair or replacement of the cable and to provide guide means for same.

The present invention is in the nature of a modification of the improvements disclosed in the co-pending application of John P. Faber, Serial No. 223,870, filed October 4, 1927. Other objects and advantages of the present improvements will be apparent to those skilled in the art by reference to the accompanying description and the drawings in which—

Fig. 1 is a side elevation of a loading bucket and connected parts broken away, embodying the improvements;

Fig. 2 is a front view of the loader bucket showing the improvements; and

Fig. 3 is an enlarged detail of one of the cable saddles or guides.

Fig. 4 is an enlarged side view of one of the cable guides;

Fig. 5 is a plan view of the member illustrated in Fig. 4.

The skip or loader bucket 1 is adapted to be raised or lowered by means of a cable 2 running over drums 3, 4, and connected with a suitable power device. The drums 3 and 4 are mounted on uprights 5 and 6 comprising part of frame 6' of the apparatus. The bucket 1 is suitably pivoted adjacent its discharge end 7, to the frame

and is arranged to tip as it is elevated and ultimately discharge its contents into a mixing drum. These details of construction are well known in the art and are therefore omitted in the drawings to avoid confusion in illustration.

On each side of the bucket, at the forward end thereof and preferably although not necessarily adjacent its horizontal bottom, are rigidly welded, riveted or otherwise secured, a pair of castings forming cable guides or saddles 10 and 10'. These guides are preferably mounted to that portion of the bucket as shown in Fig. 1, but it is understood that they may be secured in any other convenient position along the outer limits of the bucket, depending upon the load it is called upon to withstand and the speed of its elevation. In place of one such saddle on each side of the bucket or skip, a plurality of similar saddles may be mounted on each side along the forward upstanding portion (see Fig. 1) and the horizontal base portion of the bucket.

These saddles or guides are identical in configuration, except that saddle 10 presents an angle to the right while saddle 10' describes an angle to the left. But one of these elements has been illustrated in enlarged detail in Figs. 3 to 5. Referring to Figure 3, the guide or saddle 10 is shown as L-shaped, the shorter or horizontal leg being disposed along a horizontal portion of the skip, while the longer or vertical leg contacts a vertical portion thereof. When fixed in this position on the skip, it is seen that the saddles embrace angles formed by the bucket sides, affording re-inforcement therefor.

Each element 10, 10' is provided with ears 11, 11' extending the entire length of the L, and located in spaced relation to one another, each in a plane normal to the surface of the element contacting the skip. These projecting portions or ears are preferably provided, one on each side of the axial plane of the saddle, and are preferably cast thereon or may be otherwise secured so long as sufficient clearance is provided between the ears to accommodate the cable 2. As illustrated in Figs. 2 and 3 the portions 12 of the ears protrude somewhat and are provided with apertures for receiving the

removable bolt or cotter pin 13. From this portion 12, to the end of the longer leg of the L, the ears gradually increase in width (see Figs. 2 and 3), being broadest at part

5 14. Referring to Fig. 1, it is seen that the ears flare or diverge near the top of the L, the parts 14 therefore providing the deepest and widest section of the saddle or guide.

The preferred form of the ears 11, 11' is 10 more clearly seen by reference to Figs. 4 and 5 wherein lips 15 and 16 are provided on each ear. As illustrated, these lips extend laterally from each ear, at right angles thereto and are directed toward one another. They terminate a slight distance from the axial plane of the saddle, sufficient clearance being afforded between their edges to 15 freely permit the insertion and withdrawal of cable 2. As seen in Fig. 4, the lips 15 and 16 extend the entire length of the vertical legs of the L-shaped ears 11, 11', thereby forming, with said ears, a fan-shaped pocket or channel having the slit 17 for passage of the cable as above described. 20 Obviously the lips 15 and 16 may be omitted from the ears 11, 11', or they may be extended, as desired along the horizontal leg of the L-shaped ears, the construction being immaterial so long as the clearance or slit 25 17 is maintained throughout. The plan view of the saddle shown in Fig. 5, illustrates the flared or diverging arrangement of the ears 11, 11' along the horizontal leg of the saddle.

The apertures in portions 12 are so provided that when the cable is in place (see 30 Fig. 3) and the cotter pins 13 are threaded therein, the latter will be spaced from the cable, allowing freedom of movement for same in the saddle. It is apparent that the 35 pins 13 bridge ears 11, 11' outside the cable 2, thus preventing the latter from completely leaving the saddle when in use, or when slack in the cable occurs.

In use, the guides or saddles 10, 10' being 40 fixed to the bucket, the cable 2 may be looped over the end thereof and placed in the guideways or channels formed by the ears 11, 11' of the saddles after passing through slits 17. Pins 13 are then threaded 45 through the portions 12 thereby locking the cable within the saddle on each side of the bucket. When the cable is drawn taut, it will assume the position illustrated in the drawings, that is, it will be disposed along 50 the sides and lower front of the bucket and at the same time "hug" the L's 10, 10'. Since the pins 13 are spaced from the cable 2, the latter has freedom of movement through 55 the saddles and about the bucket, so that 60 during raising or lowering of the bucket, should the load be unevenly distributed therein, or the winding drums fail to function properly, equalization of the pull of the cable will result. This equalizing feature 65 obviously eliminates undesirable twisting or

torque of the bucket and enables the bucket at all times to automatically adjust itself and the load to swing in the arc of least resistance.

It is apparent that the provision and location of the saddles protects the cable against undue wear and injury or the deteriorating effect of exposure to the ground. Furthermore, aside from re-inforcing the bucket, the saddles or guides protect same 70 from wear and friction of the cable. During the arcuate travel of the bucket, the cable is given freedom of lateral movement in the channels formed by the diverging portions of the ears on the saddles. In operation the depth of the ears, the provision of lips 15, 16, and the pins 13 prevent the cable from 75 losing its position in the saddles and consequently its hold on the bucket.

An important feature of the present improvements resides in the fact that the cable 2 may be readily disconnected from the skip or bucket by merely withdrawing cotter pins 13 from the castings. When desired, the cable may be slackened, the pins removed and the cable slipped through slits 17 and looped over the bucket and without the aid of any particular tool, or disrupting the balance of the apparatus. This ability to disconnect the cable with a minimum of time and trouble is a distinct advantage in shipping, assembling or when replacing a worn cable, skip or winding drum. Other advantages of the present improvements will be apparent to those skilled in the art. 100

I claim:

1. In a device of the character described, an endless hoisting cable, a loader bucket, mechanism for winding said cable located adjacent said bucket, a cable guide having a plurality of projecting ears mounted on each side of said bucket and adjacent the base thereof, said ears terminating in inwardly extending members, said cable extending over said guides and about said bucket, and being free to move to a limited extent therethrough, and removable pins bridging the ears of each guide exteriorly of said cable, whereby said cable may be maintained on said guides, or removed therefrom without 105 injury to or severing of the cable. 110

2. In a device of the character described, a hoist bucket, a cable guide mounted on said bucket comprising a channel shaped member adapted to freely receive and surrender a cable said member having inwardly extending lips and a curved wall portion, and a removable pin spaced from the base of said channel member and bridging a portion of the open face thereof. 115

3. In a device of the character described, a cable guide comprising a base adapted to be secured to a support, a channel shaped member protruding from said base, said member defined by oppositely disposed L- 120 125 130

shaped ears, whereby to form a housing with said base.

4. In a device of the character described, a cable guide comprising a base adapted to be secured to a support, a channel shaped member protruding from said base, said member defined by oppositely disposed L-

shaped ears, whereby to form a housing with said base, and removable means bridging said ears to provide a closure for said housing. 10

Witness my hand this 19th day of January, 1928.

ANDREW S. JOHNSON.
